ENCLOSURE FOR A LOUDSPEAKER SYSTEM

John C. Shannon, Hicksville, N.Y., assignor to Empire
Scientific Corporation, Garden City, N.Y.

Filed May 7, 1973, Ser. No. 358,099

Term of patent 14 years

Int. Cl. D14—03

U.S. Cl. D26—14 G

FIG. 1.

FIG. 2.

FIG. 3.

FIG. 4.

FIG. 1 is a perspective of an enclosure for a loudspeaker system showing my new design;

FIG. 2 is a side view partially sectioned;

FIG. 3 is a bottom plan view; and

FIG. 4 is a cross-section taken on line 4—4 of FIG. 2.

I claim:

The ornamental design for an enclosure for a loudspeaker system, as shown and described.
